his Atty.

UNITED STATES PATENT OFFICE.

AUGUST C. DOBRICK, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

PRIMING CUP.

1,425,512.

Specification of Letters Patent. Patented Aug. 15, 1922.

Application filed May 28, 1919. Serial No. 300,371.

To all whom it may concern:

Be it known that I, AUGUST C. DOBRICK, a citizen of the United States, and a resident of Chicago, in the county of Cook and State 5 of Illinois, have invented certain new and useful Improvements in Priming Cups, of which the following is a full, clear, and exact specification.

My invention is concerned with improvements in priming cups, such for instance as is shown in my United States Patent No. 1,332,944, dated March 9, 1920, and is designed to produce a priming cup, which, when not in use, prevents any possibility of 10 any dirt getting into it and being carried through by the oil into the cylinder the next time it is primed. To this end, it consists of a cover attached thereto in such a manner that is can be snapped into place and will 15 be securely held covering the cup until it is again opened to prime the cylinder.

To illustrate my invention I annex hereto a sheet of drawings in which the same reference characters are used to designate identical parts in all the figures of which—

Fig. 1 is an elevation of my improved cup with the top portion thereof in central vertical section;

Fig. 2 is a top plan view of the same; and 30 Fig. 3 is a perspective view of the cover detached; and

Fig. 4 is a central vertical section showing the valve mechanism.

The priming cup shown consists of the 35 base portion 10 adapted to be screwed into the head of a cylinder, or elsewhere, and having a passage therethrough adapted to be closed or opened at will by a valve formed on the end of the valve stem 11 40 screwed therein and provided with a passage therethrough opening into the cup 12 formed on the top of the stem and preferably provided with ears 13 by which it is more readily turned. The details of the 45 internal mechanism of this valve are shown in Fig. 4, and are covered by my Patent No. 1,332,944, issued March 9, 1920.

The cover 14, best seen in Fig. 3, is preferably formed of sheet metal, and has the 50 body portion 15 of the proper outline to cover the cup 12, which outline in the present instance is circular. It has the short pivot piece 16 by which it is secured by the

55 rivet 17 on one of the ears 13. At the opposite side from the pivot piece 16 is a projection 18 preferably formed by stamping down some of the material of the body, and having its under surface projecting into the cup, and of such an outline as to fit snugly in the edge of the cup farthest 60 from the rivet 17, so as to prevent the cover from accidental movement while not preventing its being intentionally turned on its pivot 17 to open up the cup to pour oil into it. I preferably place thereon opposite 65 to the projection 16 an upwardly projecting tongue 19 by which the cover is conveniently manipulated.

What I claim as new and desire to secure by Letters Patent of the United States is: 70

1. In an apparatus of the class described, the combination with a priming cup having a receiving chamber, of a spring metal cover pivoted to one side of the top of said chamber so as to move only in a plane parallel 75 to the top of the receiving chamber, and having a segmentally shaped projection on the under side thereof adapted to fit into the further side only of the chamber top from the pivot to hold the same from accidental movement while permitting it to be turned on its pivot when desired, the projection being entirely within the chamber when the cover is closed.

2. In an apparatus of the class described, 85 the combination with a priming cup having a receiving chamber, of a sheet metal cover pivoted to one side of the top of said chamber so as to move only in a plane parallel 90 to the top of the receiving chamber, and having a segmentally shaped projection stamped on the under side thereof adapted to fit into the further side only of the chamber top from the pivot to hold the same from accidental movement while permitting it to 95 be turned on its pivot when desired, the projection being entirely within the chamber when the cover is closed, and an upwardly projecting tongue, for the purpose described.

100 In witness whereof, I have hereunto set my hand and affixed my seal, this 20th day of May, A. D. 1919.

AUGUST C. DOBRICK. [L. S.]
Witness:

JOHN HOWARD McELROY.
